Thomas Howe ATTORNEY

UNITED STATES PATENT OFFICE

ADOLPH PETELER, OF FREEPORT, NEW YORK, ASSIGNOR TO AUTO SPECIALTIES MANUFACTURING CO., OF SAN FRANCISCO, CALIFORNIA, A CORPORATION OF CALIFORNIA

LIFTING JACK

Application filed September 18, 1924. Serial No. 738,362.

This invention relates to lifting means such as the jacks for lifting the axles of vehicles and similar applications wherein devices of this character would be useful.

5 The main object of the invention is to provide a lifting jack wherein the lifting movement shall be multiplied for a given movement of the operating means so that a large lift may be easily and effectively accomplished. This is especially useful in connection with a hand operated jack for lifting the axle of a vehicle on which balloon tires are used in that this use requires a relatively large lift and, being usually operated by hand, it 10 should be operable without undue expenditure of energy or time. It is obvious, however, that this is merely one of the applications in which the invention will prove useful.

20 A further object of the invention is to provide a device of the character as indicated wherein the parts are not secured in rigid relationship but are floating, that is capable of mutual adjustment to adapt themselves to 25 the conditions of use encountered.

Other and ancillary objects of the invention will appear hereinafter.

In the accompanying drawings which illustrate the invention:

30 Fig. 1 is a side elevation partly in vertical axial section of a jack, in collapsed position, embodying the invention;

Fig. 2 is a view partly in top plan partly in transverse section as viewed on the line 35 2—2 of Fig. 1;

Fig. 3 is a side elevation on a reduced scale of the jack showing the parts in extended position; and

40 Fig. 4 is a fragmentary view showing the relationship of parts as will be hereinafter referred to.

45 Referring to the drawings, the device comprises a pedestal having a base 1 and a cylindrical sleeve 2 which may be integrally formed by casting. The interior of the sleeve 2 is formed with screw threads 3 with which engage suitable threads on a nut or collar 4. Resting upon the nut 4 is the end of a second sleeve 5 having its exterior a smooth cylindrical surface permitting it to slide longi-

tudinally or turn within the sleeve 2. The sleeve 5 also has screw-threads 6 upon its interior and a suitably threaded nut or collar 7 engages in the threads 6. Upon the nut 7 rests the end of a cylinder 8 telescoping within the sleeve 5. At the upper end of the cylinder 8 is the cap 9 for engagement with the axle or other object to be lifted, which cap may be mounted upon ball bearings as shown, and is rotatable so as to readily adjust itself to the conditions of the body acted upon.

55 As the nuts 4 and 7 are turned in one direction the nut 4 will rise in relation to the sleeve 2 and push the sleeve 5 upward ahead of it, while the nut 7 will rise with relation to the sleeve 5, pushing the cylinder 8 up ahead of it.

60 To turn the nuts 4 and 7 a central hexagonal shaft 10 is provided. A hexagonal sleeve 11, for a purpose as will be hereinafter referred to is fitted about the shaft 10 but telescopically slideable thereon. The shaft 10 passes through a hexagonal opening in the nut 4 while the shaft and sleeve pass through a similar opening in the nut 7 so that the nuts turn with the shaft and sleeve but may slide longitudinally thereof. The shaft is turned by a bevel gear 12 fitting its hexagonal form at its lower end. The gear 12 is turned 65 by a bevel gear 13 fixed to a shaft 14 journalled in the sleeve 2 and base 1 of the pedestal and extending to the outside of the base where it is provided with a squared end or other suitable conformation for engagement with a wrench or other suitable tool for turning it.

70 It will be apparent that upon turning the shaft 10 the nut 4 will rise in the sleeve 2 and with it the sleeve 5, while the nut 7 and with it the cylinder 8 will rise with relation to the sleeve 5 so that for a given movement of the shaft 14 the cap 9 will have a movement equal to the sum of the movements of the sleeves 5 and 8. It is desirable however 75 that the turning shall not be continued to cause the lifting members of the jack to move out of proper relationship to each other but that limiting means for the turning be provided. To this end a tongue 15 is formed at 80

the lower end of the sleeve 5, which tongue extends into a keyway 15' in the sleeve 2 of the pedestal, this keyway extending to a sufficient length to permit the desired movement of the sleeve 5 but the upward movement of the sleeve is limited by the tongue 15 coming against the shoulder 16 on the pedestal at the end of the keyway. It is therefore impossible to turn the shaft 14 to such an extent as to force the sleeve 5 out of the top of the pedestal. The stopping of the sleeve 5 prevents further turning of the nut 4 and therefore locks the shaft 10 so that further lifting of the nut 7 and sleeve 8 is prevented.

15 It is not only desirable that it shall not be possible to unduly operate the lifting members upwardly so that they will become disassociated as just referred to, but it is also desirable that it be not possible to pull them apart or that they fall apart when in positions other than the vertical. We have already seen that the sleeve 5 cannot leave the pedestal because of the tongue 15. To prevent the sleeve 8 from leaving the sleeve 5 is 20 the purpose of the sleeve 11 and its arrangement as will now be referred to.

25 Starting from the collapsed position as shown in Fig. 1, as the jack is raised, the nut 4 carries with it the sleeve 11 and as the nut 7 moves upwardly with relation to them, and lifts the member 8 with it, it slides upon the sleeve 11 as does also the ring 17 which is a spring ring, sprung into a groove upon the interior of the sleeve 8 in a manner well understood by those skilled in the art. When the ring 17 reaches the upper end of the sleeve 11 it engages its outwardly flared end 18 and carries the sleeve with it thereafter, the sleeve sliding upon the shaft 10. This upward movement of the sleeve 11 with relation to the shaft 10 is limited by a tongue 19 on the sleeve peened inwardly at its bottom and sliding along a flat face 20 on the shaft 10 and formed by flattening one of its angles. The upward movement of the sleeve is limited by this tongue coming against the shoulder 21 on the shaft 10 at the upper end of the flat face. In order that the sleeve 11 may be certainly carried down into the collapsed position of the jack, an outwardly projecting tongue 22 on the sleeve is engaged by the nut 7 in its downward course.

It will be seen from the foregoing that the desired multiplication of lifting is accomplished and at the same time the members are floating with relation to each other instead of being secured together so that they may adjust themselves to the conditions of lifting encountered and also the members may be pulled outwardly by grasping the cap of the jack so that the parts may be extended for purposes of inspection, cleaning or other purposes and at the same time means is provided for preventing the pulling apart or disassociation of the parts.

While the invention has been illustrated in what is considered its best applications it may have other embodiments without departing from its spirit and is not therefore limited to the structures shown in the drawings.

What I claim is:

1. A lifting jack comprising a pedestal, a lifting member adapted to be projected from said pedestal, an actuating member for said lifting member, a second lifting member adapted to be projected with respect to said first lifting member, an actuating member for said second lifting member and driving means common to said actuating members arranged in said pedestal and effective to project said first lifting member with respect to said pedestal and said second lifting member with respect to said first lifting member.

2. A lifting jack comprising a plurality of telescoping tubular members, means in one member engaging therewith and adapted to be forced therealong by relative turning, said means engaging another of said members to slide it with relation to the other member and a telescoping central shaft engaging said means to turn it but such engagement permitting sliding of said means with relation to said shaft and means for turning said shaft.

3. A lifting jack comprising a plurality of telescoping tubular members, means in a plurality of said members respectively each engaging with its respective member and adapted to be forced therealong by relative turning, said means engaging another of said members to slide it with relation to the other member and a telescoping central shaft common to all of said means and engaging therewith to turn them, but such engagement permitting sliding of said means with relation to said shaft and means for turning the said shaft.

4. A lifting jack comprising a plurality of telescoping tubular members, certain of said tubular members being interiorly threaded, a plurality of nuts engaging with the said threads upon the interiors of their respective members, each of said nuts being adapted to engage another of said members and slide it with relation to the member with which the nut is in screw-threaded engagement, a telescoping central shaft engaging with said nuts to cause turning thereof with said shaft but permitting sliding of said nuts along said shaft and means for turning said shaft.

5. A lifting jack comprising a plurality of telescoping tubular members, certain of said tubular members being interiorly threaded, a plurality of nuts engaging with the said threads upon the interiors of their respective members, each of said nuts being adapted to engage another of said members and slide it with relation to the member with which the nut is in screw-threaded engagement, a

central shaft engaging with said nuts to cause turning thereof with said shaft but permitting sliding of said nuts along said shaft and means for turning said shaft and centrally located telescoping means for preventing dissociation of said members.

6. A lifting jack in combination with a casing comprising a base and an interiorly screw-threaded sleeve, a nut engaging with the interior of said sleeve, a second sleeve sliding within the first mentioned sleeve, said second sleeve being interiorly screw-threaded, a second nut engaging with the screw threads upon said second sleeve, a cylindrical member engaging with said second nut, said sleeves and member telescoping with relation to each other, a central shaft engaging with said nuts to turn the same but permitting longitudinal sliding of said nuts along said shaft, gearing in said base adapted to drive said shaft, operating means for said gearing extending to the exterior of the pedestal, means for preventing said second sleeve from being withdrawn from the pedestal and means for preventing said cylindrical member from being withdrawn from said second sleeve, the last mentioned means comprising a sleeve telescoping with said shaft, the last mentioned sleeve engaging with said shaft and said cylindrical member at the limit of their relative movement to prevent their being moved further apart.

7. A lifting jack comprising a plurality of telescoping tubular members, certain of said tubular members being interiorly threaded, a plurality of nuts engaging with the said threads upon the interiors of their respective members, each of said nuts being adapted to engage another of said members and slide it with relation to the member with which the nut is in screw-threaded engagement, a central shaft engaging with said nuts to cause turning thereof with said shaft but permitting sliding of said nuts along said shaft and means for turning said shaft and centrally located telescoping means for preventing dissociation of said members and a rotatably mounted cap at the upper end of one of said members.

8. A lifting jack comprising a plurality of telescoping tubular members, certain of said tubular members being interiorly threaded, a plurality of nuts engaging with the said threads upon the interiors of their respective members, each of said nuts being adapted to engage another of said members and slide it with relation to the member with which the nut is in screw-threaded engagement, a central shaft engaging with said nuts to cause turning thereof with said shaft but permitting sliding of said nuts along said shaft and means for turning said shaft and centrally located telescoping means for preventing dissociation of said members and a rotatably mounted cap at the upper end of one of said

members, the said member carrying said cap being rotatable with respect to said means for preventing dissociation of said members.

9. A lifting jack including an interiorly screw threaded tubular member, a nut in engagement with the internal screw threads of said member, a second member slidably mounted within said first member and free for movement at all times towards and away from said nut, said second member being normally supported at its inner end by said nut, and means for rotating said nut.

10. A lifting jack comprising an interiorly screw threaded tubular member, a nut in engagement with the internal screw threads of said member, a second member mounted for free axial movement within and laterally supported by said first member and supported at its inner end within the tubular member by said nut, a central shaft with which said nut has sliding non-rotative engagement, and means for rotating said shaft.

11. In a jack having a frame including a tubular portion, a tubular member supported within the tubular portion and a second tubular member supported within the tubular member, a central driving member arranged within the tubular portion, and lifter means actuated directly by the driving member and co-operating respectively with the tubular portion and the tubular member to project respectively the tubular member and the second tubular member.

12. A lifting jack comprising, an upright standard having a vertically extending tubular portion, a shaft rotatably mounted in said standard, a gear rotatable with said shaft, a tubular cylindrical lifting member housed in the tubular portion of said standard, a second lifting member telescopically movable within said first mentioned lifting member and carrying a head adapted to be engaged by the portion to be lifted, separate means operable by the rotation of said gear for raising each of said lifting members whereby to project the head on said second lifting member to a raised position substantially equal to twice the height of the standard, and means for holding said outer lifting member from rotation during its raising movement.

13. A lifting jack comprising, an upright standard having a vertically extending tubular portion comprising a casing, a shaft rotatably mounted in said standard, a gear rotatable with said shaft, a tubular cylindrical lifting member housed in the casing, a second lifting member telescopically movable within said first mentioned lifting member and having a head at its upper end adapted to engage a body to be lifted, separate means operable by the rotation of said gear for raising said lifting members whereby to project the head on said second lifting member to a raised position equal to sub-

- stantially twice the height of the casing and means formed and arranged in said casing and co-operating with said tubular lifting member whereby relative rotation thereof within the casing is prevented.
14. A lifting jack having a frame including an upright tubular portion, a driving pinion rotatably mounted in the frame, a driven gear mounted for rotation in the frame, an outer tubular lifting member arranged within the tubular portion of said frame in position to be axially extended from and retracted into said tubular frame portion, a second lifting member arranged within said tubular lifting member in position to be axially extended from and retracted into said tubular lifting member, threaded means co-operating between said driven gear and said outer lifting member for moving the lifting member axially in the tubular frame portion, means formed and arranged in said frame to co-operate with said outer tubular member whereby relative rotation thereof within the frame is prevented and screw threaded means co-operating between said outer tubular lifting member and said inner lifting member whereby to effect relative axial movements of the latter with respect to said tubular lifting member.
15. A lifting jack comprising a frame having a tubular portion, a driving pinion rotatably mounted in the frame, an outer tubular lifting member arranged within the tubular portion of said frame in position to be axially extended from and retracted into said tubular frame portion, a second lifting member telescopically arranged within said tubular lifting member, threaded means operable by the rotation of said pinion for moving the tubular lifting member axially in the tubular frame portion and said second lifting member axially within said tubular lifting member, means formed and arranged in said frame to co-operate with said outer tubular lifting member whereby relative rotation thereof within the frame is prevented and screw threaded means co-operating between said outer tubular lifting member and said inner lifting member whereby to effect relative axial movements of the latter with respect to said tubular lifting member.
16. A lifting jack comprising a frame having a tubular portion, a driving pinion rotatably mounted in the frame, an outer tubular lifting member arranged within the tubular portion of said frame in position to be axially extended from and retracted into said tubular frame portion, a second lifting member telescopically arranged within said tubular lifting member, means including a gear driven by said pinion and screw threaded connecting means operable by the rotation of said pinion for raising both of said lifting members with respect to said frame, co-operating means formed and arranged between the frame and the tubular lifting member for preventing relative rotation therebetween during the axial movements of the tubular lifting member, said means including a portion arranged in one of said members to engage the other member at various points in the length thereof during the axial movement of the tubular lifting member within the frame.
17. A lifting jack comprising a frame having a tubular portion, a driving pinion rotatably mounted in the frame, an outer tubular lifting member arranged within the tubular portion of said frame in position to be axially extended from and retracted into said tubular frame portion, a second lifting member telescopically arranged within said tubular lifting member, means including a gear driven by said pinion and screw threaded means co-operating between said gear and said tubular lifting member for moving the same axially in the tubular frame portion, co-operating means formed and arranged between the frame and the tubular member for preventing relative rotation therebetween during the relative axial movement of the tubular lifting member within the frame, said means including a portion arranged in one of said members to engage the other member at various points in the length thereof, and screw threaded means co-operating between said tubular lifting member and said inner lifting member whereby to effect relative axial movements of the latter with respect to said tubular lifting member.
18. In a jack, the combination of a housing having a beveled gear mounted in the base thereof, said beveled gear being provided with an upstanding driving member, threaded means operated by the rotation of said driving member to be advanced axially thereof, a work lifting member having plain exterior surfaces and having its upper end arranged to contact with the work, and means operable by movement of said threaded means for causing the projection of the lifting member, said means including a sleeve slidably splined to the housing and shiftable axially relative to the threaded means.
19. In a jack, the combination of a housing having a beveled gear mounted in the base thereof, said beveled gear being provided with an upstanding driving member, threaded means operated by the rotation of said driving member to be advanced axially thereof, a work lifting member having its upper end arranged to contact with the work and provided with plain exterior surfaces, and means operable by movement of said threaded means for causing the projection of the lifting member, said means including a sleeve slidably splined to the housing and shiftable relative to the threaded means, said sleeve and lifting member having smooth and imperforate surfaces and adapted to enclose

portions of the jack mechanism of the jack when in extended position.

20. In a jack, the combination of a housing having a beveled gear mounted in the base thereof, said beveled gear being provided with an upstanding driving member, threaded means operated by the rotation of said driving member to be advanced axially thereof, a work lifting member having plain exterior surfaces and having its upper end arranged to contact with the work, and means operable by movement of said threaded means for causing the projection of the lifting member, said means including a sleeve slidably splined to the housing and shiftable axially relative to the threaded means, and cooperative stops on the sleeve and housing to prevent the sleeve from being extended completely out of the housing.

21. In a jack, the combination of a housing having a beveled gear mounted in the base thereof, said beveled gear being provided with an upstanding driving member, threaded means operated by the rotation of said driving member to be advanced axially thereof, a work lifting member having plain exterior surfaces and having its upper end arranged to contact with the work, and means operable by movement of said threaded means for causing the projection of the lifting member, said means including a sleeve slidably splined to the housing and shiftable axially relative to the threaded means, whereby to permit the upper end of the load lifting member to be projected to more than two times the height of the housing.

22. In a jack, a housing having a tubular upstanding portion, a driving mechanism including a beveled gear and an upstanding portion mounted in said housing, a beveled pinion meshing with said gear and rotatably mounted in the side walls of said housing to rotate the driving mechanism, screw threaded means operable upon the rotation of said upstanding portion to advance axially thereof, an outer sleeve arranged in the housing for axial projection therefrom upon the movement of said threaded means, said sleeve being axially slidable with respect to the screw threaded means and splined to the housing to prevent rotation of the sleeve in the housing, a projection member having a load engaging saddle at its upper end housed within the sleeve for projection therefrom, and threaded means operable upon the rotation of the upstanding portion of the driving mechanism to project the lifting member from the sleeve.

23. In a jack, a housing having a tubular upstanding portion enlarged at its lower end to provide means for enclosing a driving mechanism, a driving mechanism including a beveled gear mounted in said enlarged portion of the housing, a beveled pinion meshing with said gear and rotatably mounted

in the side walls of said housing, a screw threaded element and threaded means operable upon the rotation of the bevel gear to project the screw threaded element, a tubular sleeve having a smooth exterior surface arranged within the tubular portion of the base for projection therefrom by the projection of the screw-threaded element, said sleeve being capable of axial movement relative to the screw threaded element and having a splined connection with the tubular portion of the base to prevent relative rotation thereof with respect to the base, said screw threaded element being operable to project said sleeve upon operation of said driving mechanism, a lifting member having a smooth exterior and provided with a lifting saddle at its upper end, said member being mounted within the sleeve for projection therefrom and threaded means operable by rotation of the driving mechanism for causing the projection of the lifting member with respect to the sleeve.

24. In a lifting jack, the combination with a pedestal, a series of telescoping members adapted to be extended upwardly from said pedestal and to be collapsed therein, and threaded means movable axially of the pedestal for simultaneously projecting said telescoping members from said pedestal and from each other, said projecting means being entirely within said pedestal, said telescoping members having plain exteriors without exposed operating means therefor whereby the jack, when extended, presents a plain exterior free from operating screws and the like, the outermost telescoping member being slidably splined to the pedestal and being axially slidably with respect to parts of the projecting means.

25. In a device of the character described, a base member, a member extensible therefrom, a second member extensible from said first member, and means for simultaneously extending said members comprising a rotatable driving member and a floating member mounted to rotate with said driving member, and free to move axially relative to and independently of at least one of said extensible members, said floating member having a member slidably mounted thereon and threadingly engaging said first extensible member.

26. In a device of the character described, a base member, a member extensible therefrom, a second member housed within and extensible from said first member, and means for simultaneously extending said members comprising a rotatable driving member and a floating member mounted to rotate with said driving member and slidably axially relative to one of said extensible members and said driving member.

27. In a device of the character described, a base member, a member extensible therefrom, a second member extensible from said

first member, and means for simultaneously extending said members comprising a rotatable driving member and an axially movable member mounted to rotate with said driving member and a member mounted to rotate with said axially movable member and having screw-threaded engagement with said first extensible member, said axially movable member being axially movable relative to said last member.

28. In a device of the character described, a base member, a member extensible therefrom, a second member extensible from said first member, and means for simultaneously extending said members comprising a rotatable driving member and a member having screw-threaded engagement with said first extensible member and engaging said second extensible member to extend the same upon rotation thereof and means for rotating said last member keyed to said driving member and to said last member and axially movable relative thereto.

29. In a device of the character described, a base member, a member extensible therefrom, a second member extensible from said first member, and means for simultaneously extending said members comprising a rotatable driving member and a nut screw-threadedly engaging said first extensible member and engaging said second extensible member to extend the same upon rotation of said nut, and means for rotating said nut mounted to rotate therewith and with said driving member but axially movable relative to both said nut and said driving member.

30. In a device of the character described, a base member, a member extensible therefrom, a second member extensible from said first member, and means for simultaneously extending said members comprising a rotatable driving member and an axially movable member mounted to rotate with said driving member, means for limiting the outward movement of said axially movable member, and a member mounted to rotate with said axially movable member and having screw-threaded engagement with said first extensible member, said axially movable member being axially movable relative to said last member.

31. In a device of the character described, a base, a member extensible therefrom, means for holding said member from rotation relative to said base, a second member extensible from said first member, and means for simultaneously extending said members comprising a rotatable driving member, means screw-threadedly connecting said driving member with said first extensible member, a floating member mounted to rotate with said driving member and free to slide relative to one of said extensible members.

32. In a device of the character described,

a base member, a member extensible from said base, a second member extensible from said first member, a rotatable driving member, and means cooperating with said driving member for extending the extensible members upon rotation of the driving member, said means including a sleeve member rotatable with and axially movable with respect to said driving member upon rotation thereof, said member carrying a slideable collar threadingly engaging said first mentioned extensible member beneath said second extensible member whereby upon rotation of said sleeve, said second member may be extended from said first member.

33. In a device of the character described, a base member, a member extensible therefrom, means preventing rotation of said member relative to the base, a second member extensible from said first member, a rotatable driving means mounted in the base member, a floating member mounted for rotation with said driving member and axially movable with respect thereto, means cooperating with said driving means for moving said floating member and said first extensible member axially with respect to said driving member and means carried by said floating member and cooperating with said first extensible member for moving the second extensible member axially with respect to the first extensible member.

In testimony whereof I have signed this specification this 17th day of September, 1924.

ADOLPH PETELER.
